William T. Croft, Long Beach, and William G.
Goodale, Los Angeles, Calif.

Application March 22, 1948, Serial No. 145,264

Term of patent 14 years

(Cl. D2—3)

To all whom it may concern:

Be it known that we, William T. Croft and William G. Goodale, citizens of the United States of America, residing in the cities of Long Beach and Los Angeles, respectively, in the county of Los Angeles, State of California, have invented a new, original, and ornamental Design for a Siphon, of which the following is a specification, reference being had to the accompanying drawing, forming a part thereof.

Fig. 1 is a front perspective view of a siphon showing our new design;

Fig. 2 is a fragmentary rear perspective view of the device;

Fig. 3 is a front elevational view of the device;

Fig. 4 is a top plan view of the device; and

Fig. 5 is a bottom plan view of the device.

We claim:

The ornamental design for a siphon, substantially as shown.

WILLIAM T. CROFT.
WILLIAM G. GOODALE.
